Primary Examiner—Paula A. Mortimer**[57] CLAIM**

The ornamental design for a solution barrier headband, as shown and described.

DESCRIPTION

FIG. 1 is a front elevational view of a solution barrier headband showing my new design;

FIG. 2 is an enlarged right end elevational view thereof;

FIG. 3 is an enlarged left end elevational view thereof;

FIG. 4 is a top plan view thereof;

FIG. 5 is a rear elevational view thereof;

FIG. 6 is a perspective view thereof;

FIG. 7 is a front perspective view thereof, the broken line showing of the human form is for illustrative purposes only and forms no part of the claimed design; and,

FIG. 8 is a side perspective view thereof.
